MACHINE FOR DELINKING AND SEGREGATING CARTRIDGES

Harold Boehmer, Salt Lake City, Utah

Application August 11, 1947, Serial No. 767,896

3 Claims. (Cl. 86—48)

(Granted under Title 35, U. S. Code (1952),
sec. 266)

1

The invention described herein may be manufactured and used by or for the Government for governmental purposes without the payment to me of any royalty thereon.

This invention relates to a new and useful improvement in machines for de-linking and segregating cartridges and is intended more particularly to produce machines for processing cartridges of cal. .30 and cal. .50. The machine comprises a de-linking mechanism which removes the cartridges from the links and a segregating mechanism which divides the removed cartridges according to their character. The particularly novel and useful features of the machine are a single power means driving both mechanisms, the continuous de-linking of the fed belt, the automatic segregation of the classes of cartridges and the safety devices to interrupt the operation of the machine in case of malfunctioning of its elements.

While there is illustrated in the drawings filed herewith, and hereinafter fully described one specific embodiment of the invention, it is to be distinctly understood that the invention is not considered to be limited to said specific embodiment but reference for its scope is made to the claims appended hereto.

In the drawings:

Figure 1 is the front elevation of the machine, portions of its frame being broken away.

Figure 2 is the left end elevation, portions of the frame and structure of the machine being broken away.

Figure 3 is an enlarged vertical section on the line 3—3 of Figure 1, in the direction of the arrows, a portion being broken away.

Figure 4 is a developed view of the de-linking drum, parts being broken away.

Figure 5 is a vertical section on the line 5—5 of Figure 3, in the direction of the arrows.

Figure 6 is a vertical section on the line 6—6 of Figure 4, in the direction of the arrows.

Figure 7 is a diagram of the wiring circuits.

Figure 8 is an enlarged vertical section on the line 8—8 of Figure 1, in the direction of the arrows.

Figure 9 is a greatly enlarged section on the line 9—9 of Figure 8, in the direction of the arrows.

Figure 10 is a view showing extractor release switch mounted adjacent de-linking drum.

As illustrated in the drawings, the machine has a frame F of suitable angle irons. A plate 1 is hinged in frame F and has a motor M mounted thereon. (Fig. 2.) A threaded bolt 2 in plate 1 co-acts with frame F as a belt-tightener. Mo-

2

tor M has a pulley 3 connected by belt 4 to pulley 5 fixed on shaft 6 journaled in frame F and provided with a sprocket wheel 7 connected by sprocket chain 8 to sprocket wheel 9 loose on shaft 10 journaled in frame F. A spring clutch 11 serves to connect wheel 9 to shaft 10. Keyed on shaft 10 are the double sprocket wheel 12 and the single sprocket wheel 13 for powering the de-linking mechanism A and the segregating mechanism B, respectively.

The de-linking mechanism A comprises a cage A-1 and a drum A-2 rotatable therein.

The cage A-1 has circular end plates 14 and 15 suitably mounted on the top of frame F, and struts, a, b, c, d, e, f, g, h and i, bolted on the peripheries of and extending between plates 14 and 15. The drum A-2 comprises a cylindrical body 16 and end discs 17 to which body 16 is attached as by welding (Fig. 6). Discs 17 are fixed on shaft 18 journaled in plates 14 and 15 of the cage A-1, and provided on one end exterior to cage A-1 with a double-sprocket wheel 19 connected by a double-sprocket chain 20 to double-sprocket wheel 12 above mentioned.

The de-linking mechanism A is supplied with the linked cartridges through a feed throat C (Figs. 1, 2, 8) comprising tray 21, plates 22, drum 23 and rollers 24. The tray 21 (Fig. 2) has its outer end formed as a depending curved lip 21-a to facilitate the imposition of the link-belt on tray 21 and guide plates 22 are mounted on tray 21 so that they converge in the direction of feed, their inner ends 22-a being relatively spaced a distance corresponding to the length of the cartridges to be processed (Fig. 1). Tray 21 passes through a suitable orifice in frame F to provide for the feed throat C, and tray 21 is suitably supported on frame F (Fig. 2). The drum 23 is freely rotatable on shaft 25 fixed in brackets 26 mounted on frame F. Rollers 24 are mounted in the ends of drum 23, respectively, for rotation therewith. Suitable means are provided on shaft 25 to limit movement of drum 23 and rollers 24 axially of shaft 25, and to align rollers 24 with the inner ends 22-a of the guide plates 22, respectively. It will be noted that each end 22-a has an arcuate edge 22-b (Fig. 8) concentric with roller 24, the edge 22-b being closely adjacent the periphery of roller 24. The drum 23 is provided on its left end (as seen in Fig. 1) adjacent roller 24 with suitable relatively-spaced cartridge-receiving sockets 23-a, and with a peripheral flange 23-b (see Fig. 8). The tray 21 extending into the machine beyond the ends 22-a of guide plates 22 passes below drum 23 curving upwardly on an arc concentric with drum 23. It will be

30

35

40

45

50

55

noted (Fig. 1) that the guide plates 22 and rollers 24 are so related to drum 23 that the fed linked cartridges will be received between the rollers 24. The feed is such that the bases of the cartridges are aligned with sockets 23-a, their projectiles extending to the other end of drum 23. The tray 21 is spaced from the periphery of drum 23 such a precise distance that the fed cartridges, moving into the machine over tray 21, have their bases received in sockets 23-a, the flange 23-b engaging the forward portion of the case of less diameter than the base (Fig. 8).

The tray 21 has its inner end 21-b extending into cage A-1 of the de-linking mechanism A between struts *a* and *i*. It will be noted (Fig. 8) that the inner end 21-b of tray 21 is so disposed that its face supporting the fed link belt is substantially tangent to drum A-2 at its horizontal diameter. Since shafts 18 and 25 of the drums A-2 and 23 are parallelly disposed (Fig. 8), and the longitudinal axes of the cartridges seated in drum 23 are parallel with shaft 25 of drum 23, the fed cartridges are disposed substantially parallel with the body 16 when they are received in drum A-2.

The body 16 of drum A-2 has, on its end toward plate 15 of cage A-1, a series of thirty sockets 27 symmetrically disposed on the periphery of body 16, and a series of thirty sockets 28 aligned with sockets 27, respectively. As clearly shown in Figs. 3 and 8, the sockets 27 and 28 are designed to receive the links and portions of the cases embraced by the links, and the portions of the cases rearward of the links, respectively. As shown, in Figs. 1 and 4, a guide plate 29 is mounted on the face of plate 15 adjacent the end of drum A-2, and so related to the feed throat C as to guide the linked cartridges properly to sockets 27 and 28. It is obvious (Fig. 4) that the point of the projectile of the cartridge bearing against plate 29, the links are in sockets 27 and the rear portions of the cases are in sockets 28.

The body 16 is further provided with thirty trackways 30 disposed in sockets 28 and extending therefrom to end of body 16 adjacent plate 14. Slidable in each trackway 30 there is a carriage 31 (Fig. 6) suitably keyed in body 16. Each carriage 31 has an extractor 32 pivoted therein. Each extractor 32 has a cam shoulder 32-a and a grip 32b. A spring 32-c biases extractor 32 in gripping position. A release button 32-d on top of extractor 32 is provided for releasing the extractor 32 after it has functioned. The carriage 31 is provided with an upstanding post 31-a about which is rotatable a roller 31-b provided for driving the carriage 31.

The cage A-1 is provided with two cam bars 33 and 34 for driving the carriages 31 toward plates 15 and 14, respectively, to engage the cartridges and extract them from the links, respectively as the drum A-2 rotates. Bars 33 and 34 are mounted on the inner faces of the struts of cage A-1 with suitable spacers 35 to properly dispose bars 33 and 34 to bear on rollers 31-b of the carriages 31. As shown in Fig. 4, plate 33 extends under struts *h*, *i*, *a*, *b*, *c* and *d*, and is so configured as to drive carriages 31 from their maximum retracted position as they pass under strut *h* to their maximum projected position as they pass under strut *d*, and plate 34 extends under struts *d*, *e*, *f*, *g* and *h* and is so configured as to drive carriages 31 from their maximum projected position as strut *d* to their maximum retracted position under strut *h*. A guide plate 36 suitably mounted on the inner faces of the struts

of cage A-1 extends under struts *b*, *c*, and *d*, one end spaced slightly from strut *a* and its other end substantially reaching strut *e*. As shown in Figure 4, this plate 36 is disposed parallel with plate 15 and disposed over the forward part of sockets 28. A plate 37 is mounted on the struts to extend from strut *d* to strut *h* directly over the link-receiving sockets 27. A plate 38 is mounted on the struts to extend from strut *e* to slightly beyond strut *h*, and is disposed substantially parallel with the position of cam plate 34 between struts *e* and *h*, to correspond with the path of travel of carriages 31 as they are moved from under strut *e* to under strut *h*. Plate 38 serves to retain the cartridges, extracted from their links, in socket 28. Plate 39 mounted under struts *g* and *h* serves to bear on the projectiles of the extracted cartridges.

A release dog 40 is suitably mounted on strut *h* to co-act with buttons 32-d to release the extractors 32 from the extracted cartridges to permit their discharge from drum A-2. As shown in Figs. 1, 4, 6, 8 and 9, the body 16 of the drum A-2 has three peripheral grooves 41, suitably disposed relative to the link-receiving sockets 27, for the intrusion therein of stripper fingers 42 (Figs. 8, 9) on the upper open end of a link discharge chute 43. It will be noted (Fig. 8) that plate 37 extends to and meets the open end of chute 43 to prevent accidental escape of the links. As shown in Figs. 1, 3, 4 and 6, the body 16 has two peripheral grooves 44, suitably disposed relative to the cartridge-receiving sockets 28, for the intrusion therein of stripper fingers 45 (Fig. 8) for removing the extracted cartridges from the de-linking mechanism A, for delivery to the segregating mechanism B.

The segregating mechanism B comprises a delivery drum B-1 and a system of valved-chutes B-2. The segregating mechanism B is supported in frame F, in the proper relation to the de-linking mechanism A, by a pair of angle irons 46 and 47 mounted in frame F. Bearings 48 on angle-irons 46 and 47, respectively, support shaft 49 on which is fixed a single sprocket wheel 50 connected by sprocket chain 51 to single sprocket wheel 13 above mentioned.

It will be noted (Fig. 1) that chains 20 and 51, for driving drum A-1 of the de-linking mechanism A and drum B-1 of the segregating mechanism B, respectively, are provided with idler sprocket wheels 52 and 53, respectively, pivotally mounted on frame F for adjustment relative to chains 20 and 51 to serve as chain tighteners.

The shaft 49 has the segregating drum B-1 keyed thereon for rotation therewith. Drum B-1 has a peripheral flange 54 on its left end and a peripheral flange 55 on its right end, as viewed in Figs. 1 and 5. Flanges 54 and 55 are provided with twenty cartridge receiving sockets 56 and 57, respectively. Sockets 56 and 57 are aligned and so configurated as to seat the bases and tapered forward portions of the cartridges, respectively. Suitably mounted on shaft 49 there is a plate 58 bearing against the left end of drum B-1 and having a radius sufficient to close the left ends of sockets 56. A plate 59 is suitably mounted on shaft 49 and bears against a spacing collar 60 on shaft 49 and bearing against the right end of drum B-1. The radius of plate 59 is sufficient so that plate 59 extends over the right ends of sockets 57. It will be noted (Fig. 5) that the parts are so related that plates 58 and 59 serve to maintain the cartridges properly disposed

in sockets 56 and 57 and prevent axial displacement.

The chute means by which the de-linked cartridges are supplied to sockets 56 and 57, and the system of valved chutes B-2 are supported, in their proper positions in frame F, by a pair of inverted yokes 61 and 62 bolted to angle-irons 46 and 47, respectively, on opposite ends of drums B-1 (Figs. 1, 3 and 5). The upper ends of the shanks of yokes 61 and 62 are connected by spaced plates to form the intake chute for drum B-1. The stripper fingers 45 above mentioned are mounted on and project upwardly from the left plate, as viewed in Fig. 3, and the right plate is provided with an upwardly turned arcuate lip 63 co-acting with fingers 45 to form an intake throat for the cartridges stripped from the de-linking drum A-1. Hinged to the right connecting plate below the lip 63 there is a pair of spaced interconnected arcuate guide plates 64. It will be noted (Fig. 3) that plates 64 extend downwardly to the plane of the horizontal diameter of drum B-1 where they co-act with fixed arcuate guide plates 65, respectively, supported on yokes 61 and 62. Plates 64 and 65 are curved concentric with drum B-1 and are so disposed as to retain the cartridges in sockets 56 and 57 of drum B-1 against radial displacement. A leaf spring 66 mounted on strut h of the de-linking mechanism A bears against plates 64 to bias them toward drum B-1 to resiliently engage the cartridges seated in drum B-1.

The system of valved chutes B-2 (Fig. 3) has three chutes I, II and III, since the machine is designed to segregate the de-linked cartridges into three groups according to the character of charges in the cartridges. Chute I on the left (as viewed in Fig. 3) is constantly open, and chutes II and III in the middle and on the right, respectively, are valved to be opened and closed periodically.

A pair of side plates 67 and 68 are bolted to the bifurcated lower ends of yokes 61 and 62 below their supporting angle-irons 46 and 47 (Figs. 1, 3 and 5).

The inner opposed faces 67-a and 68-a of plates 67, 68, respectively (Fig. 5) are precisely spaced to provide the proper length for the intake openings of chutes I, II and III. It will be noted (Fig. 5) that these faces 67-a and 68-a lie in the vertical planes pressing through plates 58 and 59, so that the length of the said openings is slightly greater than the length of the cartridges. The plates 67 and 68 are properly slotted to receive therein the ends of the inclined dividing plates 69, 70 and 71 of chutes I, II and III, which are suitably attached to plates 67 and 68. Plates 69, 70 and 71 are so relatively spaced (Fig. 3) as to provide the proper width of chutes II and III. An end plate 72 is bolted to plates 67 and 68 and spaced from plate 69 to provide the proper width of chute I. The width of chutes I, II and III, thus provided, is slightly greater than the maximum diameter of the cartridges.

Plates 67 and 68 are provided with brackets 67-b and 68-b respectively. Slidable in bracket 67-b are the two valve members 73, and slidable in bracket 68-b are the two valve members 74 and 75 (Fig. 3). As shown in Fig. 5, these valve members 73, 74 and 75 are normally intruded into chutes II and III sufficiently to prevent passage of the cartridges into chutes II and III. As clearly shown in Fig. 3, the members 74 and 75 with which co-act their associated members 73 are so disposed as to normally close chutes II

and III, respectively. It will be noted (Fig. 5) that the inner ends of members 73 are configured to receive thereon the bases of the cartridges and the inner ends of the members 74 and 75 are configured to receive thereon the outer tapered ends of the projectiles of the cartridges. It will also be noted (Fig. 5) that plates 69, 70 and 71 are slotted to provide end ears which are suitably configured to co-act with the inner ends of members 73, 74 and 75 to guide the cartridges onto members 73, 74 and 75.

The valve members 73, 74 and 75 are reciprocated to open and close chutes II and III by operating means actuated by rotation of shaft 49 of drum B-1. Brackets 76 and 77 are bolted to the upstanding shanks of yokes 61 and 62, respectively. The bracket 76 has pivoted thereon a pair of levers 78 having their lower ends received in slots 73-a in the outer ends of valve members 73, respectively. The bracket 77 has pivoted thereon a pair of levers 79 and 80 having their lower ends received in slots 74-a and 75-a in the outer ends of valve members 74 and 75, respectively. The levers 78, 79 and 80 have crank arms 81 on their upper ends, respectively, normal to levers 78, 79 and 80. In each arm 81 there is journaled a roller 82. These rollers 82 co-act with suitable cams for rocking levers 78, 79 and 80. A cam disc 83 is keyed on shaft 49 and provided with peripheral cams 83-a and 83-b co-acting with rollers 82 on levers 78. A cam disc 84 is keyed on shaft 49 and provided with peripheral cams 84-a and 84-b co-acting with rollers 82 on levers 79 and 80. The relation 35 of the parts is such that cams 84-a and 83-a actuate rollers 82 on levers 79 and its associated lever 78 for opening valve member 74 and its associated member 73 for control of chute II, and cams 84-b and 83-b actuate rollers 82 on lever 80 and its associated lever 78 for opening valve member 75 and its associated member 73 for control of chute III. Levers 78, 79 and 80 are provided with springs 78-a, 79-a and 80-a, respectively, mounted on brackets 76 and 77, for moving levers 78, 79 and 80 to normally close valve members 73, 74 and 75. Suitable bumpers 78-b, 79-b and 80-b are mounted on angle-irons 46 and 47 to limit the cam-actuated movement of levers 78, 79 and 80.

50 Chutes I, II and III are provided at their bottoms with discharge chutes 85, 86 and 87 respectively, for discharge of the segregated cartridges from the machine. Chutes 85, 86 and 87 are bolted to plates 67, 68 and 72. A supporting plate 88 is suitably mounted under the upper portions of chutes 85, 86 and 87. Chutes 85 and 87 may be hinged to the middle chute 86 for angular displacement to relatively space the paths of flow of the discharged cartridges.

60 The machine is provided with a plurality of safety devices for automatically de-energizing the motor M and braking the driving mechanism in the event of malfunctioning of its elements. An extractor release (Fig. 1) is mounted on the de-linking mechanism A, and comprises a plunger switch 89 mounted on plate 15 of cage A-1. Switch 89 is closed by a trip 89a disposed between plate 15 and the adjacent end of drum A-2 (Figs. 4 and 10). Should one of the extractors 70 32 fail to separate a cartridge from its links, the projectile of the unseparated cartridge contacting the trip 89a closes switch 89 (See Fig. 10). A segregator release (Fig. 3) is mounted on the segregating mechanism B, and comprises a plunger switch 90 closed by a trip 91 mounted on

hinged guide plates 64. Should one of the cartridges become displaced on the drum B-1, or any foreign matter be introduced, the plates 64 yielding against spring 66 cause trip 91 to close switch 90. A segregator safety gap (Fig. 5) is provided by the slotted plates 69, 70 and 71. In the bottom of each slot there is a contact plate 92 insulated from the slotted plate to which is electrically connected a wire 93. Contact plates 92 have interconnected wires 94. Thus a gap is provided which is closed by any misplaced cartridge accidentally lodged in the slotted plates 69, 70 and 71. A clutch release (Figs. 1 and 2) is mounted on frame F adjacent the spring clutch 11, and comprises a plunger switch 95. Should the spring clutch 11 relieve, due to jamming of the driving mechanism, the clutch 11 closes switch 95.

The machine is provided with braking means (Figs. 1 and 2), comprising a brake shoe 96 co-acting with the periphery of pulley 5 which serves as a brake drum. Shoe 96 is fixed on rod 97 and is slideable in guides 98 mounted on frame F. A spring 99 bearing on frame F biases shoe 96 in engaging position. A rock shaft 100 journaled in frame F has a crank handle 101 on its end toward the front of the machine and an operating crank fork 102 on the end toward the rear of the machine. When handle 101 is moved counter-clockwise (Fig. 1), the fork, 102 engaging head 103 of rod 97 raises rod 97 compressing spring 99 and moving shoe 96 into inoperative position. Rod 97 has on its lower end a notch 97-a in which is received a latch 104 pivoted on frame F (see Fig. 1). Latch 104 is restrained by a spring-pressed catch 105. A magnet 106 mounted on frame F is provided for releasing catch 105, when magnet 106 is energized. The parts are so related that when the brake is set, in inoperative position as above described, the latch 104 engaged by catch 105 locks rod 97 in elevated position. When magnet 106 is energized, catch 105 is drawn by magnet 106 from its engagement with latch 104 which is then free to pivot releasing rod 97, for application of shoe 96. Latch 104 carries a contact member 107 for knife switch 108. When the latch 104 is rocked by the depression of rod 97 by action of spring 99, contact member 107 is moved from switch 108 to open the circuit.

The diagram of the wiring circuit (Fig. 7), for the motor M, the magnet 106 and the four safety devices above described, indicates their functioning. A manual switch 109 is provided in wire 110 from the current source. Switch 108 of the brake circuit-breaker is in this wire 110. Wire 111 connects wire 110 with motor M which is connected by wire 112 with the current source. When manual switch 109 is closed and switch 108 is closed by the inoperative position of brake shoe 96, current flows through wires 110, 111 and 112 to energize motor M to power the machine.

Wire 113 connects wire 110 with the magnet 106 which is connected by wire 114 to wires 115, 116 and 117 of switch 89 of the extractor release, switch 90 of the segregator release, and switch 95 of the clutch release, respectively, and by wire 93 to plates 69, 70 and 71 of the segregator safety gap. Switches 89, 90 and 95 are connected by wires 118, 119 and 120, respectively, with wire 112. Wires 94 of the segregator safety gap are connected to wire 112.

So long as the machine functions properly, the switches 89, 90 and 95 and the gap between wires

93 and 94 are open, and magnet 106 de-energized. Should malfunctioning of the machine cause any one of the switches 89, 90 and 95 or the safety gap to become closed, as above described, current flowing through wire 114, the closed switch or gap, and wire 112 energizes the magnet 106 which, as above described, opens switch 108 to de-energize the motor M and apply brake shoe 96 to pulley 5 to brake the driving mechanism of the machine.

The shaft 6 of the driving mechanism is provided on its end with lugs 6-a for engagement with the slotted head of a removable hand-crank for manual adjustment of the de-linking mechanism A and the segregating mechanism B.

The operation of the machine will now be described. The linked cartridges are introduced into the machine through the feed throat C being passed along tray 21 and under drum 23 (Figs. 1, 2, 8). The fed belt is so disposed that the projectiles of the cartridges are to the right (Fig. 1) and the bases to the left to fit into the sockets 23-a. The belt is passed between struts a and i of the cage A-1 (Fig. 8) and upwardly along inner end 21-b of tray 21 so that the cartridges are seated in sockets 27 and 28 of drum A-2, as shown by the cartridge in broken lines in Fig. 4. It will be noted that as the cartridges are received in sockets 27 and 28 they have been so disposed by their passage through feed throat C that the nose of the projectile bears on guide plate 29, the links are received in sockets 27 and the portion of the case rearwardly of the links in sockets 28.

In the operation, hereinafter described, of the de-linking mechanism A of the machine embodying the invention, illustrated in the drawings and hereinbefore described, the links and cartridges are separated by engaging the links in their sockets 27, to prevent any movement of the links axially of the drum A-2, and the cartridges are moved in their sockets 28 axially of the drum A-2, to withdraw the cartridges from the engaged links. It is obvious that the machine can be designed to operate so that the cartridges are engaged in their sockets 28 to prevent any movement of the cartridges axially of the drum A-2, and the links can be moved in their sockets 27 axially of the drum A-2, to withdraw the links from the engaged cartridges.

Rotation of drum A-2 causes the rear portions of the cases to pass under plate 36 as they pass from strut a to strut b thus confining the cases in sockets 28. The links pass under plate 37 as the cartridges pass from strut c to strut d, thus confining the links in sockets 27. When the cartridges are thus confined as they pass strut d, the cases are engaged by extractors 32 projected by the forward movement of carriages 31.

On engagement, the carriages 31 are retracted, the engaged extractors 32 separating the cases from the links. It is to be understood that the plate 36 has its inner face which bears on the cases sufficiently spaced from drum A-2 that its forward edge engages the rear edges of the links to prevent their retraction.

As the cartridges pass strut e, they pass from plate 36 under plate 38 as they are withdrawn from the links. The links are retained in sockets 27 until they reach strut h (Figs. 4, 8), where they are stripped from drum A-2 by fingers 42 to be received in chute 43 and discharged from the machine. As above explained, should a cartridge be not separated from its links, its projectile protruding into the space between the

forward end of drum A-2 and plate 15 will engage the trip 89a of switch 89 to stop the machine before the linked cartridge reaches the fingers 42. The separated cartridges have their projectiles engaged by plate 39 as well as their cases by plate 38 until they reach strut h to insure their retention in sockets 28. As the retracted carriages 31 pass strut h, the release dog 40 engages the buttons 32-d of extractors 32 causing them to be disengaged from the cartridges. The released cartridges, passing from under plates 38 and 39, are stripped from drum A-2 by fingers 45 and are received on the arcuate lip 63 of the feed chute for the segregating drum B-1 (Fig. 3).

It will be noted (Fig. 3) that the sockets 51 of the drum B-1 are relatively spaced somewhat greater than sockets 28 of drum A-2. It is obvious that the spacing of sockets 28 is determined by the relative spacing of the linked cartridges fed to sockets 28. The spacing of sockets 57 to receive the de-linked cartridges is determined by the details of construction of the system of valved chutes B-2. It will be noted that this increased spacing of sockets 57 over sockets 28 demands a higher rate of rotation of drum B-1 over that of drum A-2 which is provided by a greater diameter of the driving sprocket wheel 13 for drum B-2 over that of the driving sprocket wheel 12 for the drum A-2.

It is to be understood that the machine is designed to process a link belt composed of units, each of which has five cartridges arranged as follows, a single cartridge, such as a "tracer," a pair of cartridges, such as "ball," and a pair of cartridges, such as "incendiary." The segregating mechanism B processes these units, successively, to discharge the three kinds of cartridges through the chutes I, II and III, respectively.

The cartridges fed by gravity through the feed chute for the drum B-1 are seated in sockets 56 and 57 therein and are retained therein by guide plates 64 and 65 (Fig. 3).

The operation of the system of valved chutes is such that as the rotation of drum B-1 delivers each of the above-described units of five cartridges, the valve members 73, 74 and 75 close chutes II and III. When the single cartridge (tracer) in the lead position in the unit passes over closed chutes II and III, it is discharged by gravity through the constantly open chute I. As the single cartridge is discharged, the valve members 73 and 74 open chute II and the first cartridge of the first pair (ball) having passed over closed chute III is discharged by gravity through opened chute II. When the second cartridge of the first pair, having passed over the closed chute III, is discharged by gravity through the still open chute II, the valve members 73 and 75 open chute III and the first and second cartridges of the second pair (incendiary) are successively discharged by gravity through the open chute III. When the second cartridge of the second pair has been discharged, the valve members 73, 74 and 75 close the chutes II and III, and the operations are repeated for successive units.

The above-described operation of the valve members 73, 74 and 75 is produced by the peculiar configuration of the cams 83-a, 83-b, 84-a and 84-b operated synchronously with drum B-1.

It will be obvious that the segregation of the cartridges is produced by a determined relation between the rotating sockets 56 and 57 carry-

ing the cartridges and the valve members 73, 74 and 75. That is, a certain pair of sockets 56 and 57 must be ready to discharge a single cartridge when they are rotated over chute I, and the next two pairs 56 and 57 must be ready to discharge two cartridges when they pass over chute II and the third pair 56 and 57 to discharge two cartridges through chute III. To accomplish this operation, each unit of five cartridges must be received in a determined series of five pairs of sockets 56 and 57. Every fifth socket 57 of drum B-1 may bear a distinctive mark, such as a tell-tale red mark to correspond to the red marked projectile of the "tracer" cartridge. To condition the machine for operation, the driving mechanism is driven manually, slowly charging the de-linking drum A-2. The linked belt must be fed to the machine with the red marked "tracer" cartridge the first one to be received in the de-linking mechanism A, followed by the two "ball" cartridges and the two "incendiary" cartridges. As the de-linked cartridges are fed through the chute to the segregating mechanism B, they are held against entry to drum B-1 until a socket 57 having the red mark is positioned directly below the feed chute. The first fed cartridge (red marked tracer) is then allowed to drop into the proper sockets 56 and 57, and the machine is properly primed. The manual switch 109 is then closed, and the machine functions as above described.

Having described the invention, what I claim is:

1. In a machine for de-linking cartridges, the combination of a cylindrical cage comprising circular end plates and a plurality of struts mounted on the peripheries of said plates and extending therebetween; a cylindrical drum rotatably mounted in said cage concentrically therewith, said drum being provided on its periphery with a plurality of sockets for receiving the links of the cartridges and a plurality of sockets for receiving the cases of the cartridges, axially aligned with the link-receiving sockets, respectively; a plurality of carriages on the periphery of the drum and slidable axially thereof in grooves in the periphery of said drum aligned with the case-receiving sockets, respectively, each of said carriages having a post projecting radially from said drum, and a roller rotatable about each post; a cam plate, mounted on the cage struts, for co-action with said rollers to drive said carriages toward one of said cage end plates, when said drum is rotated; a second cam plate, mounted on the cage struts, for co-action with said rollers to drive said carriages toward the other of said cage end plates, when the drum is rotated; means on each carriage for grasping a socketed case when the carriage is driven by said first cam plate, and for withdrawing the grasped case from the links when the carriage is driven by the second plate; means, mounted on one of said cage struts, to disengage each withdrawing means from the withdrawn case; and means to discharge separately from the machine the withdrawn cartridges and the links.

2. In a machine for de-linking linked cartridges, the combination of a rotatable drum having a plurality of link-receiving sockets, a plurality of sockets for receiving the portions of the cases of the cartridges posterior to the links, and peripheral grooves intersecting said sockets; means, mounted adjacent said drum, for guiding the linked cartridges fed to the drum to seat said links and posterior portion in said

sockets, respectively; means, mounted adjacent said drum, for engaging said links in their sockets to immobilize said links axially of said drum; means, mounted on said drum, for grasping and moving the cartridges axially of said drum to withdraw said cartridges from the engaged links; a chute, mounted adjacent said drum, for discharging from the machine the links from which the cartridges have been withdrawn; a series of stripper fingers mounted on said chute and extending into said grooves intersecting said link-receiving sockets; a second chute, mounted adjacent said drum, for discharging from said drum the withdrawn cartridges; and a series of stripper fingers mounted on said second chute and extending into said grooves intersecting said case-receiving sockets, the parts being so related that the linked cartridges are seated in the sockets as the sockets are brought, by rotation of the drum, to the zenith of the vertical diameter of the drum, the said engaging means for the links and the said grasping and withdrawing means for the cartridges function as the seated links and cartridges are carried through substantially a half-revolution of said drum, and said stripper fingers function to transfer from their sockets the links and cartridges to the chutes, when links and cartridges are adjacent the nadir of said diameter.

3. In a machine for de-linking linked cartridges, the combination of a rotatable drum having a first plurality of peripheral link receiving grooves parallel to the longitudinal axis of said drum, a second plurality of peripheral grooves axially aligned with said first plurality for receiving the portions of cartridges posterior to said links, and a third plurality of peripheral grooves axially aligned with said second and first plurality, a projectable and retractable extractor carriage slidable in each of said third plurality of grooves, comprising a main body

portion perimetricaly engaging the sides of its corresponding groove, an extractor pivotally mounted on said body portion, resilient means for pivotally biasing said extractor into position to grasp the rim of a cartridge case, means on said extractor actuatable to counter pivot said extractor out of cartridge grasping position, a post projecting radially from said main body portion, and a roller rotatable about each said post, means adjacent said drum for supplying linked cartridges to said first and second plurality of grooves, a first cam plate mounted adjacent the periphery of said drum co-acting with said roller to project said main body portion and said extractor into cartridge grasping position as said drum rotates, a second cam plate mounted adjacent the periphery of said drum co-acting with said roller to retract said main body portion and said extractor as said drum continues to rotate to thereby withdraw said cartridge, means mounted adjacent said drum and co-operating with said first plurality of grooves to immobilize said links, whereby said cartridges are delinked as said drum continues to rotate, and stripper fingers mounted in grooves in said drum intersecting said first and second plurality of grooves for stripping said delinked cartridges and said links from said drum.

HAROLD BOEHMER.
